UNITED STATES PATENT OFFICE.

KARL MÜLLER, OF ZURICH, SWITZERLAND.

DRAWING APPARATUS.

Application filed July 22, 1920. Serial No. 398,261.

To all whom it may concern:

Be it known that I, KARL MÜLLER, a citizen of the Republic of Switzerland, residing at Zurich, Switzerland, have invented 5 certain new and useful Improvements in Drawing Apparatus; and I do hereby declare the following to be a clear, full, and exact description of the invention, such as will enable others skilled in the art to which 10 it appertains to make and use the same, reference being had to the accompanying drawing, and to letters or figures of reference marked thereon, which form a part of this specification.

15 The object of the present invention is to provide a drawing apparatus, wherein a frame, adapted to travel on a drawing board, is fitted with a blade serving as a rule, for the purpose of drawing lines parallel to 20 each other.

An exemplification of the invention is shown on the accompanying drawing, on which:

25 Fig. 1 is an elevation with parts shown in section,

Fig. 2 is a plan view, some of the parts being shown in section.

Fig. 3 is a section along line A—B of 30 Fig. 2.

Fig. 4 is a section along line C—D of Fig. 2.

Fig. 5 is a plan view of a modification to parts of the exemplification illustrated in Figs. 1—4.

35 In a sleeve 1 of a frame 7 an axle 2 is rotatably mounted, which is secured against an axial displacement with regard to the sleeve 1 by the end 3 of a set screw 4 screwed through the sleeve 1, which end 3 projects

40 into a circular recess provided on the periphery of the axle 2. Milled rollers 6 are fixed to the ends of the axle 2. The frame 7 is secured to the sleeve 1 and is provided with a vertical support 8. In the latter a

45 bolt 9 is mounted displaceably in the axial direction, and carries a disc 10 forming the key. To the bolt 9 a sprag 12, 13 is linked by means of part 11. The bolt 9 is under the influence of a helical spring 14 which tends to press the bolt 9 continuously upwards.

50 The sprag 12, 13 consists of a sleeve member 12 and a rod 13 adapted to be adjusted and fixed in the member 12, the free end of the sprag is provided with a foot part 15 having

55 a serrated edge. The sprag 12, 13 is influenced by a flat spring 16.

At a hoop shaped member 17 of the frame 7 an adjustable stroke limiting device 18 is arranged. 19 denotes a milled edge thumb screw provided on the support 8 which serves 60 to limit the movement of the bolt 9 and of the sprag 12, 13 by co-acting with the disc 10.

20 denotes a rule which is fixed to the frame 7 by needle points 21 provided on the projecting ends of the frame.

In order to utilize the described apparatus for hatching parts of drawings, the latter is placed on the sheet so that the front edge 70 of the rule 20 is in the direction in which

the hatching has to be carried out. After a line has been drawn along the edge of the rule 20, the key 10 is pressed down until it strikes against the screw 19. Thereby the

75 bolt 9 is displaced downwards and the inclination of the sprag 12, 13 increased which in its normal position rests in an oblique direction with its foot 15 against the sheet by the action of its own weight and by the pressure of the spring 16. The sprag ful-

crums on the foot 15, which is in engagement with the surface of the drawing board, and causes the whole drawing apparatus to be shifted. After another line has been

80 drawn along the rule 20, the key 10 is again 85 pressed down in order to attain a further shifting of the drawing apparatus.

In order to prevent a movement of the apparatus beyond the desired range, which might happen on account of the persistence 90

of motion of the apparatus, the energy of which is comparatively great on account of the large masses contained in the latter, the above mentioned limiting device or stop 95

18 is provided. This stop 18 is so adjusted that it co-acts with the foot 15 the moment the key 10 abuts against the screw 19, whereby a further movement of the apparatus is

100 prevented. The adjustment of thumb screw 19 provides for the spacing of the lines of the hatching.

The foot of the sprag 12, 13 can be modified in as far as it can be provided with one or more knife edges instead of with points shown on the drawing. The milled rollers 105

6 are of a comparatively heavy weight which is obtained by dimensioning the rollers correspondingly, choosing a heavy material or filling them with a heavy material.

The two rollers 6 may be replaced by one 110 long roller 23, as is shown in Fig. 5. The ends of this roller are rotatably mounted in

bearings 24 and 25, provided on the frame 26, which have the shape of loops.

The device for preventing an undesired movement of the carriage could also be so arranged that a small adjustable point 22 is provided at the lower part of the bolt of the key 9 which is so adjusted that it touches the sheet and stops the carriage the moment the sprag 13 is in the position of its greatest inclination. On the accompanying drawing the point 22 as well as the stop 18 are shown, although only one of the two is required.

Instead of the point 22 the lower end of bolt 9 can also be channelled.

The sleeve 1 can be fixed rigidly to the axle 2 by screwing up the set screw 4.

The actuating mechanism can be dispensed with if the apparatus is only used for drawing parallel lines like an ordinary T-square. To this end it is, however, not necessary to remove the actuating mechanism, it can simply be brought out of action for instance by raising part 13, the apparatus may then be shifted at will in both directions of the rotation of the carriage rollers.

I claim:

1. A drawing apparatus, comprising a frame adapted to travel over a drawing board, a rule fixed to said frame, a sprag on the frame and means to cause the sprag to engage the board and to impart a travelling motion to said frame, so that subsequent 30 positions of the rule into which it is displaced by the travelling motion of said frame are parallel to each other.

2. A drawing apparatus, comprising a frame adapted to travel over a drawing board, a rule detachably fixed to said frame, a spring loaded key displaceably mounted on said frame, a sprag connected to said key and arranged obliquely to the axis of the key, and means to cause an engagement 40 of the free end of the sprag with the drawing board so that upon a pressure on the key said sprag causes the frame to be displaced whereby subsequent positions of the rule are parallel to each other.

3. A drawing apparatus, comprising a frame adapted to travel over a drawing board, a rule detachably fixed to said frame, a spring loaded key mounted on said frame, a sprag linked to said key and arranged 50 obliquely to the axis of the key, means to cause an engagement of the free end of said sprag with the drawing board so that upon a pressure on said key said sprag causes the frame to be displaced whereby subsequent 60 positions of the rule are parallel to each other, and stopping means to engage with the free end of the sprag in order to prevent a displacement of the frame beyond a desired range.

4. A drawing apparatus, comprising a

frame adapted to travel over a drawing board, a rule detachably fixed to said frame, a spring loaded key mounted on said frame and adapted to be displaced in a vertical direction, a sprag linked to said key and arranged in an oblique direction to the axis of the key, means to cause an engagement of the free end of said sprag with the drawing board so that upon a pressure on said key said sprag causes the frame to be displaced whereby subsequent positions of the rule are parallel to each other, and stopping means adjustably fixed to the frame to engage with the free end of the sprag to prevent a displacement of the frame beyond a 70 desired range.

5. A drawing apparatus, comprising a frame provided with a rotatably mounted milled roller, adapted to travel on a drawing board, a rule detachably fixed to said frame, a spring loaded key mounted on said frame and adapted to be displaced in a vertical direction, a sprag linked to said key and arranged obliquely to the axis of the key, means to cause an engagement of the free end of said sprag with the drawing board so that upon a pressure on said key said sprag causes the frame to be displaced whereby subsequent positions of the rule are parallel to each other, and stopping means adjustably fixed to the frame to engage with the free end of the sprag to prevent a displacement of the frame beyond a 80 desired range.

6. A drawing apparatus, comprising a frame provided with heavy rollers rotatably mounted on said frame and adapted to roll on a drawing board without gliding, a rule detachably fixed to said frame, a spring loaded key mounted on said frame and adapted to be displaced in a vertical direction, a sprag linked to said key and arranged obliquely to the axis of the key, means to cause an engagement of the free end of said sprag with the drawing board so that upon a pressure on said key said sprag causes the frame to be displaced whereby subsequent positions of the rule are parallel to each other, and stopping means adjustably fixed to the frame to engage with the free end of the sprag in order to prevent a displacement of the frame beyond a 90 desired range.

7. A drawing apparatus, comprising a frame provided with rollers and adapted to travel on said rollers over a drawing board, a rule detachably fixed to said frame, a spring loaded key mounted on said frame and adapted to be displaced in a vertical direction, a sprag linked to said key and arranged obliquely to the axis of said key, means whereby the length of said sprag may be adjusted, means to cause an engagement of the free end of said sprag with the drawing board so that upon a pressure on said key said sprag causes the frame to be dis- 100 110 120 130

placed whereby subsequent positions of the rule are parallel to each other, and stopping means adjustably fixed to the frame to engage with the free end of the sprag to prevent a displacement of the frame beyond a desired range.

8. A drawing apparatus, comprising a frame provided with rollers and adapted to travel on said rollers over a drawing board, 10 a rule detachably fixed to said frame, a spring loaded key mounted on said frame and adapted to be displaced in a vertical direction, a sprag linked to said key and arranged obliquely to the axis of said key, 15 means whereby the length of said sprag may

be regulated, means to cause an engagement of the free end of said sprag with the drawing board so that upon a pressure on said key said sprag causes the frame to be displaced whereby subsequent positions of the rule are parallel to each other, and an adjustable foot provided on the lower end of the key and resting on the drawing board when the key is pressed down to prevent a displacement of the frame beyond a desired range.

In testimony that I claim the foregoing as my invention, I have signed my name.

KARL MÜLLER.
